UNITED STATES PATENT OFFICE.

STANLEY R. GREENE, OF CLEVELAND, OHIO, ASSIGNOR OF ONE-HALF TO DAVID T. CROXTON, OF CLEVELAND, OHIO.

TUYÈRE STOCK.

1,405,683.

Specification of Letters Patent. Patented Feb. 7, 1922.

Application filed July 7, 1919. Serial No. 308,964.

To all whom it may concern:

Be it known that I, STANLEY R. GREENE, a citizen of the United States, resident of Cleveland, county of Cuyahoga, and State 5 of Ohio, have invented new and useful Improvements in Tuyère Stock, of which the following is a specification, the principle of the invention being herein explained and the best mode in which I have contemplated applying that principle, so as to distinguish 10 it from other inventions.

My invention relates to tuyère stocks and particularly to tuyère stocks intended for use in hot blast furnaces.

15 The annexed drawing and the following description set forth in detail certain means embodying my invention, the disclosed means, however, constituting but one of the various mechanical forms in which the principle of the invention may be applied.

In said annexed drawing:

Figure 1 represents a central longitudinal section of my new and improved tuyère stock in connection with the blow pipe and 25 a fragmentary portion of the water-jacketed tuyère;

Figure 2 represents a view similar to Figure 1, upon an enlarged scale, of an improved elbow section of tuyère stock forming 30 my invention, showing a fragmentary section of a straight section of stock connected thereto; and

Figure 3 represents a side elevation of the parts shown in Figure 2.

35 Referring to the annexed drawing, there is disclosed a tuyère stock consisting of a section 1 adapted to be connected to the bustle pipe, not shown, and a section 2 adapted to be connected to the blow pipe 3.

40 A fragmentary section of the usual water-jacketed tuyère is indicated by the ordinal 4. The adjacent machined ends of the sections 1 and 2 are so connected as to allow for swivel or rotary motion between said sections and the same are held to proper contact by means of the eye bolts 5 and related parts, as plainly shown in the drawing.

The adjacent machined ends of section 2 and the blow pipe 3 are removably held to 45 the proper contact by means of the spring-held rod 6, as also plainly shown in the drawing. All of the above is well known practice, as known to those skilled in the art.

50 My invention consists in providing an unlined elbow section 2 for use in a hot blast

furnace, said section being comprised of cast steel. Furthermore, my invention consists in providing such a section of comparatively short length which, in combination with the unlined feature thereof, provides such a section of tuyère stock which is very light and very easily handled, more easily adjusted to the joints, etc. Furthermore, such a short length of the elbow section, together with the curve which I have given to the same, 60 enables the elbow to be thoroughly and readily cleaned, inasmuch as from the top thereof, by means of a straight poker, the accumulation at the bottom can be forced directly out of the lower open end. 70

I have further provided an eye-sight opening of improved construction. Said improvement consists in forming this opening 7 of much smaller diameter than has heretofore been utilized and locating this 75 opening upon the curved back of the elbow section 2 and not substantially in the plane of the bottom of said section, so that the draft traveling around the curve tends to keep the opening clear from dust, etc. Heretofore this eye-sight opening has been of a size substantially the full diameter of the 80 elbow section.

I have found it unnecessary to line the cast steel section because of its greater elasticity. The results in reducing the weights of the section are very noticeable. For instance, a lined cast iron section of normal size would weigh from six hundred (600) to eight hundred (800) pounds; a very light 85 lined cast iron section would weigh as much as four hundred (400) pounds. The normal weight for my unlined cast steel section is two hundred (200) pounds. 90

What I claim is:

1. In a hot blast furnace tuyère stock; a blow pipe section leading into the furnace; a pipe section independently supported at an angle thereto and adapted to be connected to the bustle pipe; and an associated 100 short unlined elbow section curved substantially from end to end adapted to be removably supported between said pipe sections in engagement with the ends thereof. 95

2. In a hot blast furnace tuyère stock, the combination with a straight section thereof, terminating adjacent the furnace opening and angularly disposed with respect to the axis of said opening; of an associated unlined cast steel elbow section adapted to be 110

removably supported with one end thereof in engagement with the straight section and its other end in alinement with said opening.

3. In a furnace tuyère stock, the combination with a vertical section thereof; of an elbow section of comparatively short length in which substantially the whole of the elbow bottom lies in planes intersecting the elbow top and not intersecting the vertical side walls of the elbow, whereby accumulations at the bottom can be forced directly from the top out of the lower end.

4. In a furnace tuyère stock, the combination

of a straight pipe section, terminating adjacent the furnace opening; of a curved 15 elbow section connected at one end to said pipe section and having its other end in alinement with said opening and provided in the curved back thereof, with a relatively minute peep opening in alinement with the 20 furnace opening, said opening being unobstructed to permit of a continuous flow of air therethrough.

Signed by me, this 17th day of June, 1919.

STANLEY R. GREENE.
